DESIGN FOR A WASHING MACHINE

Jacques Stanitz, Warren, Ohio, assignor to Prima
Manufacturing Company, Inc., Sidney, Ohio,
a corporation of Ohio

Application December 18, 1935, Serial No. 60,147

Term of patent 3½ years

To all whom it may concern:

Be it known that I, Jacques Stanitz, a citizen of the United States, residing at Warren, in the county of Trumbull and State of Ohio, have invented a new, original, and ornamental Design for Washing Machines, of which the following is a specification, reference being had to the accompanying drawing, forming a part thereof.

In the drawing:

Figure 1 is a perspective of a washing machine showing my new design;
Figure 2 is a side elevation thereof;
Figure 3 is a top plan view thereof;
Figure 4 is a section on the line 4—4 of Figure 2, looking in the direction of the arrows.
I claim:

The ornamental design for a washing machine substantially as shown.

JACQUES STANITZ.
